(57) **CLAIM**

The ornamental design for a rocking chair with underseat storage, as shown and described.

DESCRIPTION

FIG. 1 is a top left perspective view of the rocking chair with underseat storage of the present invention;

FIG. 2 is a top view thereof;

FIG. 3 is a front view thereof;

FIG. 4 is a left side view thereof;

FIG. 5 is a right side view thereof;

FIG. 6 is a top right perspective view thereof; and,

FIG. 7 is a top right perspective view illustrated with the seat in an open position.

The portions of the rocking chair with underseat storage illustrated in broken lines form no part of the claimed subject matter.
